UNITED STATES PATENT OFFICE.

CHARLES K. TETER, OF CLEVELAND, OHIO, ASSIGNOR TO THE TETER MANUFACTURING COMPANY, OF CLEVELAND, OHIO, A CORPORATION OF OHIO.

FACIAL INHALER.

1,244,661.

Specification of Letters Patent. Patented Oct. 30, 1917.

Application filed September 9, 1912. Serial No. 719,389.

To all whom it may concern:

Be it known that I, CHARLES K. TETER, a citizen of the United States, residing at Cleveland, in the county of Cuyahoga and State of Ohio, have invented certain new and useful Improvements in Facial Inhalers, of which the following is a specification.

My invention relates to improvements in a facial inhaler, designed for use in connection with anesthetizing apparatus, and has for its object the provision, first, of an inhaling device, which will be self-adapting to the features of the patient, for the purpose of excluding the air; second, which will permit the observation of the patient's features, for the purpose of detecting any retching; third, which provides a positive, adjustable pressure-valve, and finally one which may be readily and effectually sterilized. The structural details of my improvement will be more readily understood, by making reference to the accompanying drawings, wherein:—

25 Fig. I, is a view in side elevation of my improved facial inhaler.

Figs. II, and III, are enlarged longitudinal sectional views of the adjustable positive pressure-valve, preferably employed therein.

30 Fig. IV, is a transverse sectional view of said valve on line IV—IV.

Fig. V, is an under-side plan view, partially broken away, of my improved inhaler, and

35 Fig. VI, is an enlarged fragmentary view of the pressure-gage.

Throughout the several figures of the drawings, I have employed the same character of reference to indicate similar parts.

40 In order to observe the features of the patient at all times, I provide a substantially bell-shaped body *a* of transparent material, preferably celluloid. About the outer rim of said body, there is secured the oval pneumatic cushion *b*, provided with a substantially circular apron *c* integral therewith, and formed of soft rubber. The said apron fits closely upon the lower edge or rim of the body *a*, while the pneumatic cushion, which is adapted to be inflated through the valve *d*, provides a self-conforming member, which fits over the nose

and about the mouth of the patient, so closely, as to exclude the air therefrom. Under these circumstances, the patient is compelled to breathe the anesthetizing vapors or gases supplied to the bell-shaped body, through the angular duct *e*. In order to maintain a positive, determinable pressure, for the purpose of inducing and continuing anesthesia under the desired conditions, there is provided the pressure-valve *f*, positioned opposite the duct, upon the upper surface of the body *a*. Accordingly, these members are so disposed as to afford the least interference with the observation by the surgeon of the patient's condition, through the transparent celluloid walls *a*. This material is preferred, not only because of its transparency, but it is light in weight, flexible and yet sufficiently rigid, to mount the valve and duct thereon.

In order to increase the absorption by the blood, of the anesthetizing gases or vapors, the positive pressure-valve is provided for insuring a constant pressure within the respiratory organs of the patient. This valve comprises the aluminum disk *g* normally closing the valve-opening, under the tension of spring *h*, positioned interiorly of the slotted tube *i*. At the side of said tube is a graduated scale indicating the compression of the spring, necessary to secure gas pressures ranging between two (2) and twenty-four millimeters, for example. The exterior sleeve *j* has a set-screw *k* which turns within the cylindrical plug *l* positioned above the upper end of spring *h*. Thus the valve may be set at any desired pressure, and will require no attention upon the part of the operator.

It will be observed that the valve-part or disk *g* is provided with a relatively long depending stem *m*, which slides readily within the sleeve *n*, but serves to center said disk *g*, and seat it closely and evenly, to close the valve-opening.

The valve and duct are removably secured to the celluloid body, by means of interposed rubber washers *o*, and interior screw rings *p*, which afford substantially gas-tight joints between these parts.

This is important, for the reason that an essentially novel and distinct method of

anesthesia is obtainable with the comparatively simple apparatus herein set forth. Prior to my invention, inter-thoracic surgery has been dependent upon anesthesia 5 maintained under pressure, as in a room wherein super-atmospheric pressure is secured by suitable means.

- Inasmuch as my inhaler is adapted to close or cover both the nose and mouth, 10 while a definite adjustable gas-pressure may be maintained therein and in the respiratory organs of the patient, it is clear that the lungs will not suffer collapse but may be distended thereby, throughout anesthesia or 15 indeed, as long as is required. Moreover, such pressure is subject at all times to the control or accurate regulation of the surgeon or operative, dependent upon the varying condition of the patient.
- 20 It will be observed that the pneumatic cushion is disposed immediately beneath the edges of the celluloid body-portion, whereby the pressure upon the face of the patient may be light and yet sufficient to 25 permit any necessary working-pressure for the anesthetic.

Casual consideration will show that all the parts of my inhaler are readily accessible for inspection, replacement or adjustment, and 30 that they are so designed as to permit of very ready and effectual sterilization. The rubber cushion and apron may be replaced at small cost, while the other parts are not subject to deterioration or damage from ordinary use.

Having now described the preferred embodiment of my invention, I claim as new and desire to secure by Letters Patent, the following:—

- 40 1. The combination with an inhaling device having an inhaler-member, of an associated valve affording a relatively large clearance therefor; a spring normally acting to close said valve, an adjustable part for 45 varying the tension exerted by the spring against the valve, a slotted casing for the spring, and a gage associated therewith; all visibly and accessibly mounted upon the inhaler-member, substantially as set forth.
- 50 2. The combination with an inhaling device, having an inhaler member and a free valve opening, of a valve-part normally closing the same, a slotted tubular casing above said valve-part, a relatively long 55 spring therein acting against said valve-part, a member extending through said slotted casing for varying the tension of the spring, and means for securing said member at predetermined points along said casing 60 for insuring positive pressure within the inhaling device; all visibly and accessibly mounted upon the inhaler-member, substantially as set forth.

3. In an inhaling device, the combination

65 with a substantially bell-shaped body-portion formed of celluloid and free from obstructing members externally and internally thereof; of suitable inlet and outlet members connected therewith, and a soft rubber apron equipped with a peripheral pneumatic cushion; said cushion being normally positioned beneath the lower edges or rim of said body-portion, substantially as set forth.

70 4. In an inhaling device, the combination with a substantially bell-shaped body-portion, formed of transparent material having unobstructed sides, of suitable inlet and outlet members connected therewith, a peripheral pneumatic cushion positioned adjacent to the rim or edges of the body-portion, and an inflating valve and stem therefor extending alongside of the pneumatic cushion in position not to obstruct the view through 75 said body-portion, substantially as set forth.

80 5. In an inhaling device, the combination with a substantially bell-shaped body-portion, formed of transparent material, of a gas inlet disposed upon the body-portion, and a positive pressure valve, comprising an adjustable spring governing the tension of the 85 valve, a gage and means for setting the tension of the spring at the different points indicated by the gage; all visibly and accessibly mounted upon the body-portion, substantially as set forth.

90 6. The combination with an inhaling device having an inhaler member, of a valve-part governing the exhalation therefrom, a gage and adjusting means controllable therefrom for regulating the valve and accurately varying the exhaling-pressure from 95 said device; all visibly and accessibly mounted upon the inhaler-member, substantially as set forth.

100 7. In apparatus of the class described, the combination with a substantially bell-shaped member of transparent celluloid having unobstructed sides, of inlet and outlet valves positioned wholly upon the top of said body portion and a pneumatic cushion disposed 110 upon the lower edges of said body portion, whereby its sides are entirely free and unobstructed, substantially as set forth.

115 8. In a facial inhaler, the combination with an open-bottom bell-shaped body-portion, of means for sealing its edges in engagement with the face of the patient, a gas-inlet, and an adjustable-pressure exit-valve, comprising a valve-part, a coiled spring longer than the diameter of said valve-part, 120 means for adjustably tensioning the pressure of said spring upon the valve-part substantially throughout the length of the spring, and a gage for indicating such adjustment; all visibly and accessibly mounted 125 upon the body-portion, substantially as set forth.

9. In apparatus of the class described, the

combination with a substantially frusto-conical inhaling member of transparent character, of exhaling and inhaling valves positioned thereon; the former comprising a valve member, a relatively long light pressure spring, a gage, and means for adjusting the spring in accordance with the indications of the gage; all accessibly mounted

upon the inhaling member, substantially as set forth.

In testimony whereof I do now affix my signature in the presence of two witnesses.

CHARLES K. TETER. [L.S.]
